Fig. 1.

Fig. 2.

Fig. 3.

Fig. 4.

FIG. 1 is a perspective view of a cup dispenser, showing our new design.

FIG. 2 is a perspective view thereof, similar to FIG. 1, but showing the cup dispenser rotated approximately 100°.

FIG. 3 is a sectional view taken substantially along the line 3—3 in FIG. 1.

FIG. 4 is a bottom view of the dispenser.

Our design is characterized by a substantially tubular body having a plurality of spaced internal ribs extending upwardly with a wide portion at their bottom and tapering to a narrow portion at their termini.

We claim:

The ornamental design for a cup dispenser, substantially as shown and described.
